United States Patent Office

Des. 191,435
Patented Oct. 3, 1961

191,435

FLOOR MAT

Abraham I. Kantor, 122 Cleveland Terrace,
Bloomfield, N.J.

Filed June 16, 1959, Ser. No. 56,376

Term of patent 14 years

(Cl. D9—6)

FIG. 1

FIG. 2

FIG. 3

FIG. 4

FIGURE 1 is a view of one quarter of a floor mat embodying my new design, the remaining three quarters are substantially the same.

FIGURE 4 is a sectional view along lines 4—4 of FIGURE 1.

I claim:

The ornamental design for a floor mat, as shown and described.
